ATTORNEY.

UNITED STATES PATENT OFFICE.

JOSEPH HENRY FRIEDT, OF ESTEVAN, SASKATCHEWAN, CANADA.

POCKET-COMB.

1,323,463.

Specification of Letters Patent.

Patented Dec. 2, 1919.

Application filed March 25, 1919. Serial No. 285,115.

To all whom it may concern:

Be it known that I, JOSEPH HENRY FRIEDT, a subject of the King of Great Britain, residing at Estevan, in the Province of Saskatchewan and Dominion of Canada, have invented certain new and useful Improvements in Pocket-Combs, of which the following is a specification:

This invention is a pocket comb and has for its principal object the production of an efficient means for incasing the comb when the same is carried within the pocket of a garment.

Another object of this invention is the production of a removable sheath which may be slipped over the comb when the comb is to be carried within the pocket of a garment, although the sheath may be readily removed when the comb is to be used.

Another object of this invention is the production of a sheath which is comparatively flat to receive a comb while a portion of the sheath is constructed to extend into a supporting handle of the comb for forming a tight closure and preventing the entrance of dust or refuse into the sheath when the comb is carried therein.

One practical form of construction and assembly of the present invention will be hereinafter described and is illustrated in the drawing, in which:

Figure 1 is a side elevation of the device.

Fig. 2 is a side elevation, showing the sheath partly removed.

Fig. 3 is a central longitudinal section through the device the comb being shown in elevation.

Fig. 4 is an inverted detail perspective view of the sheath.

Fig. 5 is a transverse vertical section taken on the line 5—5 of Fig. 3.

In the preferred embodiment of the present invention, to be hereinafter specifically described, it will be seen that the back 10 of the comb has the usual teeth 11 extending therefrom as shown in Fig. 3. The back 10, however, extends a considerable distance beyond the teeth and is carried by an elongated plug 12 which is firmly received within the cylindrical cap 13. It will be noted that the plug 12, however, terminates short of the open end of the cap for a purpose to be hereinafter set forth. The device may therefore be used simply by the user gripping the cap 13 and using the comb in the usual manner since the teeth will be

carried beyond the end of the cap. The sheath is indicated in general at 14 and comprises an elongated substantially cylindrical rib 15 which is hollow and is slotted longitudinally as shown at 16. The body of the sheath comprises a longitudinal bridge portion 17 from which extends the walls 18. The walls 18 are joined upon the bridge portion in any suitable manner, the rib 15 adjacent the slot 16 thereof, it being noted that one end of the sheath has a closed wall 19. The body of the sheath, however, terminates short of one end of the rib 15 as shown in Fig. 4.

When it is desired to carry the comb within the pocket of a garment, the sheath may be slipped thereover as shown in Figs. 1 and 2. This is accomplished by the receiving of the back 10 of the comb within the rib 15 while the teeth 11 are received within the pocket of the sheath. As the sheath slips over the comb, the projecting end of the rib 15 will be passed into the cap 13 owing to the shortness of the plug 12 as shown in Fig. 3. Therefore sufficient frictional engagement will be presented, owing to the split end of the rib 15 to firmly hold the sheath in detachable engagement with the cap 13.

If so desired, a retaining grip may be provided upon the cap 13 as indicated in dotted lines at 20 in Fig. 1. Under such conditions, therefore, when the sheath is carried over the comb, the sheath may be placed in the pocket of the garment and at this time the grip 20 may engage the garment pocket for firmly holding the device in a convenient position for access thereto, and at this time only the cap 13 will be projecting where the same may be seen.

When it is desired to use the comb the cap 13 may be gripped and pulled outwardly from the pocket of the garment, thus removing the comb and sheath therewith. The sheath 14 may be gripped and slipped from over the comb and the comb used in the usual manner. After this action has taken place the sheath may again be slipped over the comb in the manner hereinbefore specified and the projecting end of the rim 15 passed into the cap and thus releasably connect the sheath to the cap.

It will therefore be seen that a very simple structure has been provided for guarding the comb when the same is not in use, the device being formed from a minimum num-

ber of parts and thus minimizing the possibility of the same becoming broken or injured when in use, while the simplicity of the structure will reduce the cost of production.

Also the slatted construction of the rib 15 will cause the rib to firmly bind upon the cap to hold the device in disassembly when not in use.

10 The foregoing description and accompanying drawing have reference to what might be considered to be the approved or preferred form of my invention. I desire it to be understood that I may make such changes 15 in the construction, combination, and arrangement of parts, materials, dimensions, etcetera, as may prove expedient and fall within the scope of the appended claim.

Having thus fully described my invention 20 what I claim as new and desire to secure by Letters Patent, is:—

In a device of the character described, the combination of a comb back having teeth thereon, said back extending for a considerable distance beyond the end of the teeth, 25 a plug carried on the projecting end of said back and terminating short of said teeth, an elongated cap positioned over said plug and extending to a point contiguous to said

teeth although being spaced from said back a sheath comprising a substantially cylindrical elongated rib having a longitudinally extending slot throughout its entire length, a bridge portion having walls connected to said rib upon opposite sides of said slot, whereby the bridge portion is substantially U-shaped in cross section, one end of said bridge portion and said rib being closed, the remaining end of said bridge portion and said rib being open, said last mentioned end of said bridge portion terminating short of the last mentioned end of said rib, whereby said comb back and teeth may be inserted into said rib and said bridge portion, while said cap will fit over the projecting end of said rib and the rear end of the teeth will fit at the open end of said bridge portion, thus causing the cap and teeth to form a closure for the sheath at its open end whereby refuse will be prevented from entering into the sheath of the comb when the sheath is carried thereover.

In testimony whereof I affix my signature in presence of two witnesses.

JOSEPH HENRY FRIEDT.
